(57) **CLAIM**

The ornamental design for a carry case for percussion quartz crucible, as shown and described.

DESCRIPTION

FIG. 1 is a perspective view of a carry case for percussion quartz crucible showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the carry case for percussion quartz crucible; and,

FIG. 10 is a perspective view of the carry case for percussion quartz crucible where the carry case for percussion quartz crucible is in a close state.
